Ivar Jepson and Robert O. Ernest, Oak Park, Ill., assignors to Sunbeam Corporation, Chicago, Ill., a corporation of Illinois

Application June 7, 1954, Serial No. 30,837

Term of patent 14 years

(Cl. D81—10)

To all whom it may concern:

Be it known that we, Ivar Jepson and Robert O. Ernest, both residents of Oak Park, Illinois, whose respective post office addresses are 637 Bellefonte Street, and 1220 North Hayes Avenue, have invented a new, original, and ornamental Design for a Frying Pan, of which the following is a specification, reference being had to the accompanying drawings, forming a part hereof.

Fig. 1 is a perspective view of a frying pan embodying my new design.

Fig. 2 is a top plan view of Fig. 1 somewhat reduced in size; and

Fig. 3 is a side elevational view of Fig. 2.

We claim:

The ornamental design for a frying pan, substantially as shown.
